UNITED STATES PATENT OFFICE.

LEROY S. BUFFINGTON, OF MINNEAPOLIS, MINNESOTA, ASSIGNOR TO
WARREN T. WALKER AND GEORGE THWING, OF MINNEAPOLIS,
MINNESOTA.

BELT.

SPECIFICATION forming part of Letters Patent No. 689,352, dated December 17, 1901.

Application filed December 15, 1900. Serial No. 39,969. (No model.)

To all whom it may concern:

Be it known that I, LEROY S. BUFFINGTON, a citizen of the United States, residing at Minneapolis, in the county of Hennepin and State 5 of Minnesota, have invented certain new and useful Improvements in Belts; and I do hereby declare the following to be full, clear, and exact description of the invention, such as will enable others skilled in the art to which 10 it appertains to make and use the same.

My present invention has for its object to provide an improved belt adapted to be worn by men to support their trousers and by women to support their skirts; and to these 15 ends the invention consists of the novel devices and combinations of elements hereinafter described, and defined in the claim.

The invention is illustrated in the accompanying drawings, wherein like characters indicate like parts throughout the several views.

Figure 1 is a perspective view of one of my improved belts of a design adapted to be worn either by a man or woman. Fig. 2 is a perspective view of a belt designed especially to 20 be worn by a woman. Figs. 3 and 3^a are supplemental views with parts broken away, showing in plan sections of the belt. Figs. 25 4, 5, and 6 are plan views showing sections of the belt with various garment-fasteners applied thereto. Fig. 7 is a section on the line $x^7 x^7$ of Fig. 3^a. Fig. 8 is a section on the line $x^8 x^8$ of Fig. 4. Fig. 9 is a section on the line $x^9 x^9$ of Fig. 5. Fig. 10 is a section on the line $x^{10} x^{10}$ of Fig. 6, and Fig. 11 is a transverse section through a belt of slightly-modified construction.

The numeral 1 indicates the body of a belt, the same as shown having at one end a suitable buckle 2. This belt is of course preferentially constructed of leather.

The belt 1 is provided on its inner side with opposing or reversely-projecting flanges 3, preferably formed of the same strip of leather as the body 1, turned inward against the body 45 of the belt and stitched, as indicated at 3^a. These flanges 3 extend approximately from end to end of the belt, and together with the body of the belt they form an open or slotted sheath or runway, which is adapted to receive 50 the buttons or heads of the garment-fasteners and to permit them to be slipped or slid

longitudinally through the said sheath or the belt to be slipped endwise over the said buttons or fastenings. In Fig. 11 the opposing free edges of the flanges 3 are simply cut and left with their natural flexibility. For many purposes, however, it is advisable to stiffen or reinforce these flanges 3, and this in the other views of the drawings is accomplished by turning the reduced edges of said flanges 60 around longitudinally-extended pliable wires 4, as best shown in Figs. 7 to 10, inclusive, and securing them by lines of stitches 3^a. These wires while they do not make the belt too stiff to be properly manipulated and secured by the buckle give the flanges 3 such rigidity that they will securely hold the buttons or other garment-supports.

In Figs. 8, 9, and 10 the numeral 5 indicates a portion of a pair of trousers, or it 70 might be assumed to be a portion of a skirt, and in Figs. 9 and 10 the numeral 6 indicates a portion of a shirt-waist.

In Figs. 4 and 8 the numeral 7 indicates a button secured to the band portion of the 75 trousers 5.

In Figs. 5 and 9 the numeral 8 indicates a hook secured to the band of the trousers or skirt 5.

In Figs. 6 and 10 the numerals 9 and 10 indicate a pair of buttons or heads connected by a crank-like stem 11. The button 9 is held by the flanges of the belt, and the button 10 projects on the inner side of the band of the trousers 5 and is passed through a suitable buttonhole in the band of the shirt-waist 80 6. Any desired number of these devices 9 10 11 may be employed, and they serve to hold down the band of the shirt-waist. It will of course be understood that even when 90 these devices are employed the belt will be applied to buttons on the band of the trousers in the manner indicated in Figs. 4 and 8.

When the buttons or garment-fasteners are applied between the longitudinal flanges 3 of 95 the belt, it is of course evident that the belt may be slipped over the same or drawn longitudinally without pulling on the said buttons, and it is also evident that the buttons may be secured at any point, and hence do 100 not require to be located or spaced apart with reference to the belt. This permits the

belt to be applied and then drawn up to the desired size and shifted endwise in any desired position. Also it is evident that no parts of the fasteners or buttons are exposed to view when the belt is applied.

What I claim, and desire to secure by Letters Patent of the United States, is as follows:

A belt constructed of leather or similar material, provided on its inner face with longitudinally-extended inturned flanges, spaced

apart and coöperating to form an open or slitted sheath, and pliable stiffening wires or metal strips applied to the free edges of both of said flanges and coöperating to hold the 15 buttons, substantially as described.

In testimony whereof I affix my signature in presence of two witnesses.

LEROY S. BUFFINGTON.

Witnesses:

WARREN I. WALKER,
F. D. MERCHANT.
